DESIGN FOR A COSMETIC JAR

Carl Weeks, Des Moines, Iowa, assignor to The Armand Company, Des Moines, Iowa, a corporation of Iowa

Application June 18, 1935, Serial No. 57,312

Term of patent 14 years

To all whom it may concern:

Be it known that I, Carl Weeks, a citizen of the United States and a resident of Des Moines, in the county of Polk and State of Iowa, have invented a certain new, original, and ornamental Design for a Cosmetic Jar, of which the following is a specification, reference being had to the accompanying drawing, forming part thereof:

I claim:

The ornamental design for a cosmetic jar substantially as shown.

CARL WEEKS.
